(57) **CLAIM**

The ornamental design for drink tray, as shown and described.

DESCRIPTION

FIG. 1 is a top perspective view of a first embodiment of a drink tray of the present design;

FIG. 2 is a bottom perspective view of the drink tray of FIG. 1;

FIG. 3 is a top plan view of the drink tray of FIG. 1;

FIG. 4 is a bottom plan view of the drink tray of FIG. 1;

FIG. 5 is a left side view of the drink tray of FIG. 1;

FIG. 6 is a right side view of the drink tray of FIG. 1;

FIG. 7 is a top perspective view showing the placement of five drink containers in the holes in the drink tray of FIG. 1;

FIG. 8 is a top perspective view of a second embodiment of a drink tray of the present design;

FIG. 9 is a bottom perspective view of the drink tray of FIG. 8;

FIG. 10 is a top plan view of the drink tray of FIG. 8;

FIG. 11 is a bottom plan view of the drink tray of FIG. 8;

FIG. 12 is a left side view of the drink tray of FIG. 8;

FIG. 13 is a right side view of the drink tray of FIG. 8;

FIG. 14 is a top perspective view showing the placement of seven drink containers in the holes in the drink tray of FIG. 8;

FIG. 15 is a top perspective view of a third embodiment of a drink tray of the present design;

FIG. 16 is a bottom perspective view of the drink tray of FIG. 15;

FIG. 17 is a top plan view of the drink tray of FIG. 15;

FIG. 18 is a bottom plan view of the drink tray of FIG. 15;

FIG. 19 is a left side view of the drink tray of FIG. 15;

FIG. 20 is a right side view of the drink tray of FIG. 15; and,

FIG. 21 is a top perspective view showing the placement of six drink containers in the holes in the drink tray of FIG. 15. The broken line illustrations of drink containers in FIGS. 7, 14, and 21 are for the purpose of illustrating environmental structure and form no part of the claimed design.
